Patented Apr. 25, 1922.

UNITED STATES PATENT OFFICE.

ARLINGTON MOORE, OF BOSTON, MASSACHUSETTS, ASSIGNOR TO CLARKE-MOORE CORPORATION, OF WILMINGTON, DELAWARE, A CORPORATION OF DELAWARE.

METHOD OF FABRICATING PAPER CONTAINERS.

1,413,759.

Specification of Letters Patent. Patented Apr. 25, 1922.

Application filed September 9, 1920. Serial No. 409,166.

To all whom it may concern:

Be it known that I, ARLINGTON MOORE, a citizen of the United States, residing at Boston, in the county of Suffolk, State of Massachusetts, have invented certain new and useful Improvements in Methods of Fabricating Paper Containers; and I do hereby declare the following to be a full, clear, and exact description of the invention, such as 10 will enable others skilled in the art to which it appertains to make and use the same.

The present invention relates to methods of fabricating containers from any suitable fibrous stock whether paper or resembling 15 paper, and particularly for forming parts thereof, more especially the neck and portions of the closure, with a plurality of folds of stock. The paper stock may be single or multiple ply with or without incorporating 20 a binder, and the container may be in the form of a firkin, or have any suitable polygonal or curved form.

In the construction of paper containers, I have found it desirably to form such parts 25 of the container as the neck and portions of the closure of a plurality of folds of stock. Such folds provide not only an increased thickness of stock to work in the formation 30 of the parts and upon which to construct the closure, but also to reinforce the container and closure against external and internal pressures. Irrespective of the form 35 of the container or closures therefor, or of the means employed whether manual or mechanical, the plurality of folds of stock are formed according to the method of the present invention, preferably from a continuation of the side wall, by doubling back and then reversely folding the terminal portion 40 of the stock or the side wall. Where the folded part is to consist of three folds of stock, for example, in the ledge to support the cap of the container, the doubled-back and reversely-extended portions of the 45 side wall are each folded in adjusted amount depending upon the size of the ledge, or upon the amount the ledge is to extend into the container to compensate for changes in 50 gage dimensions due to manufacturing inaccuracies and expansion and contraction of the blanks before forming. And, where the folded part consists of three folds to form, for example, the neck of the container, the doubled-back and reversely-extended portions 55 of the side wall are each folded in ap-

proximately the same amount to produce a neck triply enforced throughout. In this construction the side wall is preferably doubled back inwardly to form a hem and the terminal portion thereof is extended in reversely folded position within the hem and in contact with the folded edge thereof.

Whether or not the folded part consists of three folds of stock, and forms the neck or a portion of the closure, the invention comprehends as another of its parts the method of forming a plurality of folds of stock, which consists of rotating the stock and then doubling back and reversely folding the terminal portion thereof. Where 60 mechanical means is employed to form the folds, either such means or the stock may be rotated in forming the folds. Irrespective, however, of whether the stock is rotated, but preferably so, the folds may be 65 subjected to a high pressure sufficient to bring the meeting surfaces of the stock in intimate contact or in consolidation, thus producing a highly compressed and practically solidified mass rigidly set to permanent 70 gage dimensions.

Whether or not the stock is rotated in forming the folds, or the folds subjected to a high pressure to fix them to permanent gage dimensions, the invention further comprehends as another of its parts the method of forming a portion of the container with a plurality of folds of stock, which consists in doubling back and reversely folding the terminal portion thereof and then molding 80 the folds. The stock may be rotated in forming the folds which may then be molded, preferably under a high pressure. In the method specifically described herein-after, the operation consists in successively 85 rotating the container, doubling back and reversely folding the side wall thereof, and then molding the folds thereof under a high pressure.

The accompanying drawings illustrate the 90 preferred method of forming the folds of stock, that is, by mechanical means, the mechanism shown being, however, merely 95 illustrative of the steps comprising the method and the mechanical movements involved therein.

Fig. 1 is an elevation, partly in section, of the mechanism illustrative of the method of forming the folds; Fig. 2 is a plan view along the line 2—2 of Fig. 1; Fig. 3 is a sec- 100 105 110

- tional view along the line 3-3 of Fig. 1; Fig. 4 is a section along the line 4-4 of Fig. 3; Fig. 5 is a section along the line 5-5 of Fig. 3; Figs. 6 and 7 are detail plan and 5 side views respectively of the tools for forming the folds prior to the advancement of the tool for reversely folding the stock; Figs. 8 and 9 are similar views showing the position of the tools after the completion of 10 the formation of the folds; Figs. 10 and 11 are similar views showing the tools in position to be withdrawn; Fig. 12 is a sectional detail of the upper part of a finished container in which the folded portion forms 15 a triple-enforced neck having an outward bulge to provide a cap-retaining groove; and Fig. 13 is a similar view showing three folds of stock formed into a ledge to support the cap of the container.
- 10 The mechanism comprises a rotating die 1 having a conical shaped bore 2 and a molding surface 3 at its outer end. The die 1 is set in a gear 4 which is mounted on ball bearings 5 to rotate within a housing 6. 20 The gear 4 is driven by a pinion 7 keyed to a shaft 8 which is connected to driving means (not shown). Held within the bore of the die by means of a plug 9 is the paper stock 10 from which the container is formed. 25 The plug 9 is mounted on a shaft 11 and turns on ball bearings 12, the shaft 11 being adjustably secured at 13 in a hub 14.
- 30 The folds of stock are formed by means of a tool 15 for doubling back the stock, and 35 a hook-shaped tool 16 for reversely folding the stock. The tool 15 consists of a rod having a bent portion 15^a, with a bore 19 therethrough, which forms a curved surface 18, a similarly bent and extended portion 40 20, and a shank 17. The hook-shaped tool 16 is secured at the end of the shaft 21 which extends through the bore 19. Both tools are positioned at one side of the axis of the die as illustrated in Figs. 2 and 3. Supporting 45 the tool 15 is a frame 22 having a bearing 23 in which the extended portion 20 of the tool is fastened and a bearing 24 in which is adjustably secured, as at 25, one end of a rack shaft 26, the other end of which 50 is mounted to reciprocate in a bearing 27. Meshing with the rack shaft 26 is a toothed segment 28 keyed to a shaft 29 which is connected to driving means controlled by cams (neither being shown) for imparting 55 to the segment an intermittent rotary motion which in turn intermittently reciprocates the rack shaft 26, the frame 22, and the tool 15 mounted therein. The frame 22 has a bearing 30 supporting a portion 31 of the shaft 21, the diameter of which is slightly 60 greater than the shaft to provide a shoulder 32. The interior of the bearing 30 has a spiral cam groove 33 in which fits a pin 34 projecting from the portion 31 of the shaft 65 21. Extending beyond the shoulder 32 is

a portion 35 of the shaft 21 which is secured in a rack bushing 36 between the shoulder 32 and a collar 37 pinned at 38 to the end of the shaft. Meshing with the rack bushing is a pinion 39 keyed to a shaft 40 which 70 is connected by driving means controlled by cams (neither being shown) for producing an intermittent rotary motion to reciprocate the tool 16 and move it relatively to the tool 15. 75

In the method illustrated, the top portion of the container is formed with a plurality of folds, the operation being as follows: Prior to the advancement of either of the tools against the stock, the die is rotated at 80 about 500 revolutions per minute by means of the shaft 8 through the pinion 7, and the terminal portion of the stock projects beyond the face of the die. The tool 15 is then advanced against the stock and in virtue of 85 its position at one side of the axis of the die, the edge of the stock is engaged, as at 41, first by the shank 17 of the tool 15 and turned over as shown at 42 in Fig. 4. Upon further rotation of the stock, the curved surface 18 of the tool 15 tangentially engages 90 the turned over edge thereof, as at 43, Figs. 3 and 5, and doubles the stock backwardly, as at 44, the stock following, and being shaped by, the curved surface. Simultaneously the tool 16 is advanced against the stock in the reverse direction, being drawn backwardly from the position shown in Figs. 6 and 7 to the operative position in Figs. 8 and 9, while the hooked portion 45 is 100 turned at an angle to the tool 15 and toward the stock. The hooked portion 45 engages the edge of the stock and reversely folds it, as at 46, thus completing the folding operation. The tool 16 is now extended forwardly and the hooked portion turned away from the folds into the position shown in 105 Figs. 10 and 11 to clear the work when both tools are withdrawn.

It is evident that by adjusting the movement of each of the tools 15 and 16 against the stock, the amounts which the doubled back portion 44, and reversely extended portion 46, are folded may be varied to produce, for example, portions folded approximately in the same amount, or in varying amounts, depending upon the requirements of the part of the container to be formed. The folded portions thus formed may be pressed against the molding surface 3 by 110 any well known form of expansible die inserted within the die 1, to form, for example, a container having a triple-enforced neck 115 47 and an outwardly bulging part 48 to form a cap-retaining groove 49, as illustrated in Fig. 12, or three folds of stock to form a ledge 50, as illustrated in Fig. 13. Furthermore, the folds so molded may be subjected to a high pressure of about four 120 to six thousand pounds per square inch to 130

render them highly compressed and practically solidified and to set them to permanent gage dimensions.

Having thus described my invention, what

5 I claim is:

1. In the fabrication of paper containers, the herein described method of forming a neck of three folds of stock from a continuation of the side wall thereof, which consists in inwardly doubling back the side wall to form a hem, and then extending the terminal portion thereof in reversely folded position within the hem and in contact with the folded edge thereof. 10
2. In the fabrication of paper containers, the herein described method of forming a portion of the container with a plurality of folds of stock, which consists in rotating the stock and then doubling back and reversely folding the terminal portion thereof. 15
3. In the fabrication of paper containers, the herein described method of forming a portion of the container with a plurality of folds of stock, which consists in doubling back and then reversely folding the terminal portion of the stock by mechanical means while either the latter or the stock is rotated. 20
4. In the fabrication of paper containers, the herein described method of forming a portion of the container with a plurality of folds of stock, which consists in doubling back and reversely folding the terminal portion of the stock and then subjecting the folds to a high pressure. 25
5. In the fabrication of paper containers,
- the herein described method of forming a portion of the container with a plurality of folds of stock, which consists in rotating the stock, doubling back and reversely folding the terminal portion thereof, and then subjecting the folds to a high pressure. 30
- the herein described method of forming a portion of the container with a plurality of folds of stock which consists in doubling back and reversely folding the terminal portion thereof, and then molding the folds. 35
- the herein described method of forming a portion of the container with a plurality of folds of stock, which consists in rotating the stock, doubling back and reversely folding the terminal portion thereof, and then molding the folds to a high pressure. 40
- the herein described method of forming a portion of the container with a plurality of folds of stock which consists in doubling back and reversely folding the terminal portion thereof, and then molding the folds. 45
- the herein described method of forming a portion of the container with a plurality of folds of stock, which consists in rotating the stock, doubling back and reversely folding the terminal portion thereof, and then molding the folds. 50
- the herein described method of forming a portion of the container with a plurality of folds of stock, which consists in rotating the stock, doubling back and reversely folding the terminal portion thereof, and then molding the folds. 55
- the herein described method of forming a portion of the container with a plurality of folds of stock, which consists in rotating the stock, doubling back and reversely folding the terminal portion thereof, and then molding the folds under a high pressure. 60
- the herein described method of forming a portion of the container with a plurality of folds of stock, which consists in successively rotating the container, doubling back and reversely folding the terminal portion of the side wall thereof, and then molding the folds under a high pressure. 65
- the herein described method of forming a portion of the container with a plurality of folds of stock, which consists in successively rotating the container, doubling back and reversely folding the terminal portion of the side wall thereof, and then molding the folds under a high pressure. 70

In testimony whereof I affix my signature.

ARLINGTON MOORE.
